**CHEMICAL CONTAINER FOR ATTACHMENT TO
A DOG'S COLLAR OR SIMILAR ARTICLE**

Arthur W. Bozard, P.O. Box 45,
Holly Ridge, N.C. 28445

Filed Nov. 3, 1971, Ser. No. 195,536

Term of patent 14 years

Int. Cl. D30—08

U.S. Cl. D30—43

FIG. 1 is a perspective view of a chemical container for attachment to a dog's collar or similar article, showing my new design;

FIG. 2 is a front elevational view;

FIG. 3 is a rear elevational view;

FIG. 4 is a side elevational view;

FIG. 5 is an opposite side elevational view;

FIG. 6 is a top plan view; and

FIG. 7 is a bottom plan view thereof.

I claim:

The ornamental design for a chemical container for attachment to a dog's collar or similar article, as shown.
